UNITED STATES PATENT OFFICE.

PATRICK YORKE, OF WASHINGTON, PENNSYLVANIA.

DERRICK.

No. 877,624.

Specification of Letters Patent.

Patented Jan. 28, 1908.

Application filed September 16, 1907. Serial No. 392,957.

To all whom it may concern:

Be it known that I, PATRICK YORKE, a citizen of the United States, residing at Washington, in the county of Washington and State of Pennsylvania, have invented certain new and useful Improvements in Derricks; and I do hereby declare the following to be a full, clear, and exact description of my invention, such as will enable others skilled in the art to which it appertains to make and use the same.

This invention constitutes an improvement on my former patent No. 852,486 May 7, 1907. The material differences being in the formation of the plate and the manner of adjusting the girths and braces.

I will now describe my invention, reference being had to the accompanying drawings, in which,

20 Figure 1, is a side elevation of my improved derrick. Fig. 2, is a plan view of one of the outside section plates and Fig. 3, is a similar view of one of the inside section plates.

25 Similar letters of reference indicate corresponding parts in the different figures of the drawings.

A, represents the sill; B, the uprights or corners of the derrick; C, the girths and F, 30 the braces.

As will be seen the several sections of the derrick are clamped together by means of plates as in my former patent above referred to, but I do not use the separate plates for 35 the braces as shown in said patent. Instead I drill a series of holes in the bar of the T-iron, as indicated by the reference letter a, and bore a hole in the ends of the brace which is adapted to register with the holes in 40 the T-irons, and by passing a bolt through these holes rigidly clamp the brace in position. The two ends of the bar of the T-iron are provided with slots b, instead of holes and

slots as in the former patent, as I have found by practice that this is more convenient than 45 the holes.

The girths are preferably formed of 2" x 8" material instead of square material as I have found this to be more convenient and lighter. These girths are also held in position by 50 means of the plates and bolts. It has also been found necessary in practice to make two forms of T-irons, one a male for the outside and one a female for the inside of the joint. As will be seen by reference to Fig. 3, 55 a slot c, is formed in this plate for the purpose of admitting the bar of the plate D. This is a necessity as the plates engage all four sides of the corner or upright of the derrick. The angle-irons at the base and crown 60 of the derrick are made in about the same manner as the T-irons, being formed with a slot in one end and the series of holes in the opposite end.

From actual experience with this derrick 65 it has proven to be a much better, simpler and cheaper derrick than any other form of derrick known to our business.

Having described my invention, what I claim is:

The combination with the corner uprights, 70 girths and braces, of male and female T-irons and angle-irons, provided with a series of holes in the stem and slots in the ends of the bar for receiving bolts for clamping the 75 sections, girths and braces in a rigid position, all substantially as and for the purposes shown and described.

In testimony that I claim the foregoing as my invention, I have hereunto set my hand 80 in the presence of two witnesses.

PATRICK YORKE.
